UNITED STATES PATENT OFFICE.

DANIEL W. COMBS, OF NEEDMORE, WEST VIRGINIA.

ATTACHMENT FOR TRACTION-ENGINES.

SPECIFICATION forming part of Letters Patent No. 704,736, dated July 15, 1902.

Application filed April 16, 1902. Serial No. 103,185. (No model.)

To all whom it may concern:

Be it known that I, DANIEL W. COMBS, a citizen of the United States, residing at Needmore, in the county of Hardy and State of 5 West Virginia, have invented a new and useful Attachment for Traction-Engines, of which the following is a specification.

This invention relates to certain improvements in traction-engines, and has for its principal object to provide an improved form of mechanism in the nature of an attachment which may be applied to any ordinary form of traction-engine and employed for the purpose of assisting in the movement of the engine over soft road-beds or holes or gullies in the field and which may also be used as an auxiliary transmitting mechanism for furnishing power to a threshing-machine or other mechanism requiring power.

10 A further object of the invention is to so construct the mechanism and its supporting-frame as to permit of a reversal of a number of the elements to permit the attachment of the device to either a right-hand or a left-hand engine without any change whatever in the details of construction or mode of operation.

15 A still further object of the invention is to so construct and arrange the mechanism as to place the same wholly under the control of the engineer or attendant, the movable members of the shifting mechanism being connected by suitable operating-rods to the rear of the engine.

20 With these and other objects in view the invention consists in the novel construction and arrangement of parts hereinafter described, illustrated in the accompanying drawings, and particularly pointed out in the appended claims.

25 In the drawings, Figure 1 is a longitudinal sectional elevation of an attachment for traction-engines constructed and arranged in accordance with my invention. Fig. 2 is a front elevation of the principal parts of the mechanism. Fig. 3 is a plan view of the mechanism. Fig. 4 is a perspective view of a detail of construction. Fig. 5 is a similar view of an improved form of anchor for holding the 30 end of the hauling-line.

Similar characters of reference are employed to indicate corresponding parts throughout the several figures of the drawings.

In the employment of traction-engines for driving and hauling agricultural machinery 55 and similar purposes much difficulty is experienced in traveling the engine over sandy or soft soil and over uneven ground and in other places where the weight of the engine causes it to sink deeply into the ground or 60 where the wheels cannot get sufficient purchase to move the engine or the threshing or other machine to which it is attached. To overcome this difficulty and to provide the engine with an auxiliary power-transmitting 65 shaft, I provide a mechanism which may be secured to the front end of any ordinary form of traction-engine.

In the drawings, A designates the front end of the boiler of an ordinary form of traction-engine, and B the main driving-shaft, to which motion is transmitted by the usual engine. On this shaft are mounted a belt or fly wheel C and a sprocket-wheel D. On each side of the boiler are secured horizontally-disposed bars 10, which may be partially supported by curved bands 11, bolted to the shell of the boiler and to the bars 10. The bars 10 carry vertically-disposed bars 12, united at their upper ends by transversely-disposed 70 bars 13 and 14 and connected by brace-bars 15 to the bands 11, so as to form a rigid structure, and near the forward end of each bar 10 is secured a vertical bar 17, connected to the horizontal bar by a diagonally-disposed brace 75 18. These bars constitute the main supporting-frame of the attachment; but an auxiliary frame comprising a pair of horizontally-disposed bars 20 and a cross-bar 21 is bolted to one side of the main frame in such manner 80 that its position may be reversed when necessary to suit the style of traction-engine to which it is to be applied or, in other words, to accommodate engines having the driving mechanism on either the right-hand side or 85 the left-hand side of the boiler. The bars 20 of the auxiliary frame are secured by bolts 22 to the vertically-disposed bars 12 and 17, and as the arrangement of these bars is the 90 same on each side of the mechanism the aux- 95 100

iliary frame may be readily changed from one side to the other by the engineer, if necessary, although usually the mechanism will be adjusted at the factory before shipment. In 5 either event the expense of special castings for both right and left hand machines is avoided.

On the under side of the bars 10 are boxes 23 for the reception and support of a horizontally-disposed shaft 24, the bars 10 being preferably provided with passages 25, through which lubricant may be supplied to the bearings. The shaft 24 carries a winding-drum 26, having end flanges 27, and to the end 15 flanges and the shaft are secured gear-wheels 28, which may be intermeshed with driving-pinion 29, secured to a shaft 30, when it is desired to revolve the winding-drum. One end of the shaft 24 extends out under the 20 auxiliary frame 20 and is supported by a hanger 31, depending from said auxiliary frame, while on the extreme end of the shaft is secured a worm 32, which may engage a worm-wheel 33, carried by a shaft 34, adapted 25 to bearings on the auxiliary frame. This shaft 34 acts to reciprocate a traverse mechanism for properly guiding the hauling-line to the winding-drum, as more fully described hereinafter.

30 Near the upper end of the bars 17 is fulcrumed a rectangular frame 35, the opposite end of which rests on suitable stops 36, projecting from the vertical bar 12. The pivoted frame is provided with blocks 37 for the support of the shaft 30, which carries the driving-pinion 29, before referred to. On one end of the shaft 30 is secured a sprocket-wheel 38, to which motion is imparted from the main driving-sprocket D through the medium of 35 link-belt 39. The opposite end of the shaft 30 projects out beyond the outer end of the auxiliary frame 20 and carries a belt-wheel 40, to which may be attached a suitable belt to a threshing or other machine requiring 40 power. Near the outer end of the shaft 30 is a bearing-block 41, carried by a bar 42, having end sockets fitting over the upper ends of standards 43, carried by the auxiliary frame 20, there being suitable openings 44 arranged 45 at each standard and a similar opening 45 at each end of the bar 42 for the reception of a locking-bolt 46, which may be employed to lock the bar in either elevated or depressed position and in either case serving to rigidly 50 hold said bar and so support the outer end of the shaft 30.

Extending rearwardly from each bar 12 is a bracket 50, in which are journaled the opposite ends of a rock-shaft 51, the latter serving 55 to support a pair of notched disks 52, arranged one near each end of the shaft. The disks are provided with alining notches forming shoulders 53, adapted to engage the rear bar of the pivoted frame 35, and when the 60 rock-shaft is turned said shoulders serve to elevate the frame and separate the teeth of

the gears 28 and 29 or when turned in the opposite direction permit the descent of the frame by gravity to intermesh said gears. To the rock-shaft is secured an arm 55, from 70 which extends a connecting-rod 56 to any suitable point on the machine within convenient reach of the engineer.

57 designates a rod having a horizontal portion guided in suitable openings in the bar 12 and bracket 50, one of such rods being disposed on each side of the machine. The forward ends of the rod project over the top of the pivoted frame 35 when the latter is in the depressed position (shown in Fig. 1) and serve 80 to hold the frame down and keep the gear-teeth intermeshed. When the frame is elevated with the gear-wheels disconnected, the rods serve as a support for holding said frames in the elevated position, excessive upward movement of the frame being prevented by stops 58, carried by the vertical bars 12. After passing rearwardly through the vertical arm of the bracket 50 each of the rods 57 is provided with a downwardly and inwardly 85 bent portion 59, adapted to engage in one or other of a pair of locking-slots in the disk 52. When the arm 59 is in engagement with the lowermost slot 60, the frame 35 is in the lowest position, and any rotative movement is 90 prevented by the engagement of the arm and slot, while the movement of the arm into the slot 61 serves to lock the disk against rotative movement when the frame 35 is elevated. To provide for the movement of the locking-rods, 95 I employ a rock-shaft 60', the opposite ends of which are adapted to suitable bearings in the opposite side bars 12. Secured to said shaft at points just within the bars 12 are a pair of rocker-arms 61', having suitable openings for the reception of arms 62, projecting laterally from the rods 57 through suitable slots formed in the inner faces of the bars 12. The arms 61' are normally held forward or 100 in the locking position by springs 63, having one end connected to the arms and the opposite end connected to the vertical arm of the bracket 50. The rock-shaft 60' is further provided with an arm 65, the upper end of 105 which is connected by a rod 66 to any suitable operating lever or handle within convenient reach of the engineer.

When the mechanism is in the position illustrated in full lines in the drawings, the teeth of the gears 28 and 29 are engaged, and 110 power is transmitted to the winding-drum 26 to effect the winding of a hauling-line 67, the opposite end of which may be secured to a suitable anchorage and the winding up of the line serving to cause a forward movement of 115 the engine. At this time the locking-rods 57 are in engagement with the upper surface of the frame 35, so that any upward movement of said frame is prevented, while the disks 52 are also held from rotative movement by 120 the engagement of the arms 59 of the locking-rods in the slots 60. When the engineer 125

wishes to disconnect the gear-wheels and employ a shaft 30 and its belt-wheel 40 as a means of transmitting power to a separate mechanism, such as a threshing or other machine, he first removes the pins 46 from the alining opening 44 and 45 of the block-carrying bar 42 on the auxiliary frame. The rods 66 are then pulled toward the rear, moving the locking-rods out of engagement with both 5 the pivoted frame and the disks 52. When the rods are in unlocking position, the rod 56 is pulled to the rear, causing an angular movement of the rock-shaft 51 and the disks 52, the shoulders 53 of the latter engaging with 10 and raising the frame 35 until the rear end of the latter is at a point above the level of the locking-rod. The locking-rods are then released and are moved forward by the springs 63, the forward ends of said rods passing under 15 the frame 35 and holding the latter in elevated position, while the arms 59 of said rods pass into the slots or notches 61 and lock the disks against further rotative movement. The pins 46 are then inserted in the proper 20 openings of the auxiliary-frame standards 43 and bar 42 to form a rigid support for the outer end of the shaft 30.

When the winding-drum is being employed to wind up the hauling-line 67, it becomes desirable 25 to employ some means for properly guiding the rope on the drum and to prevent chafing the line. To the forward end of the main frame are secured two transversely-disposed bars 70, having guiding-grooves in their 30 adjacent faces for the reception of a substantially rectangular sliding frame 71, to the upper and lower bars of which are secured spindles for the reception of guiding-rollers 72, between which the hauling-line 67 is passed. 35 One end of the frame 71 is connected by a rod 73 to a crank 74, carried by the shaft 34, and as said shaft is rotated by the worm 32 and worm-wheel 33 the slide receives a reciprocating movement as the drum revolves. The 40 worm-gearing is so proportioned that the slide 71 will be moved once across the face of the drum during the time required for the drum to receive one complete coil or layer of the line, so that the latter will be wound evenly and 45 regularly, while the rollers 72 serve to prevent any chafing of the line. Projecting from the upper front end of the main frame are a pair of brackets 80, connected to the upper guide-bar 70 by braces 81, the latter being in 50 turn connected to the vertical bars 12 by braces 82 in order to make the frame as rigid as possible. In the main frame and in the brackets 80 are bearings for the support of the reduced end portions of a pair of horizontally-disposed rollers 83 and a pair of vertically-disposed rollers 84, the whole presenting an anti-friction-surface with some portion of which the hauling-line is always in contact.

When the usual driving mechanism of the 55 engine is insufficient to propel the engine when applied in the ordinary way, the haul-

ing-line is attached to some stationary point, as a tree or other object, and the winding-drum is revolved to wind up the line and cause the forward movement of the engine, 70 and in similar manner the engine may be anchored or blocked up in any suitable manner to prevent movement and the end of the line attached to an agricultural or other machine which it may be desired to move. When any 75 natural anchorage is not accessible, I employ the apparatus shown in Fig. 5 to hold the outer end of the line. This apparatus comprises a curved blade 90, preferably having a toothed lower edge, as indicated at 91, and 80 provided with eyes 92 for the reception of the curved ends 93 of a bifurcated frame 94, the opposite end of which is provided with a yoke 95, adapted to embrace a post or stake 96, which is driven into the ground at a convenient distance from the engine. The stake 96 has one or more openings for the reception of a pin 97. When the anchor is to be employed, the stake is driven into the ground, and over said stake is placed a ring 98, 85 secured to one end of the hauling-line. The pin 97 is then inserted in one of the openings at a point above the ring to prevent the latter from sliding off over the top of the stake. The blade 90 is then placed under the line, 90 and the arms of the frame 94 are inserted in the eyes 92, the line passing through the frame, as shown in Fig. 5. The toothed portion of the blade is then forced into the ground and the frame bent down until its 100 yoked end is in engagement with the upper portion of the stake, thus forming a brace and support for the stake and preventing any movement of the latter during the winding of the line. In some cases the blade 90 may be 105 dispensed with and the pointed ends of the arms 93 forced into the ground, although in loose soil it is preferred to employ the blade, owing to the increased surface area of the anchor in contact with the ground. As a 110 convenient means of carrying the anchor when not in use I employ a suitable hook 99, carried by the upper transverse bar 13, and a yoke or guard 100, carried by the bar 14 of the frame. 115

The attachment is of simple and inexpensive construction and, as before described, may be readily applied to either a right-handed or left-handed engine by changing the position of the auxiliary frame and the 120 parts carried thereby and reversing the position of the shafts 24 and 30. The attachment may also be employed on stationary or other engines for transmission of power or for the purpose of employing the drum and hoisting-line to raise weights or operate a crane or similar mechanism.

While the construction herein described and illustrated in the accompanying drawings is the preferred form of the device, it is 130 obvious that various changes in the form, proportions, size, and minor details of the

structure may be made without departing from the spirit or sacrificing any of the advantages of the invention.

Having thus described my invention, what I claim is—

- 5 1. An attachment for traction-engines, comprising a supporting-frame, a pair of shafts carried thereby, gearing connecting said shafts, a winding-drum carried by one of the 10 shafts, a hauling-line connected to said drum, and means for moving one of said shafts toward and from the other to connect and disconnect the gearing.
- 15 2. An attachment for traction-engines, comprising a supporting-frame having a movable portion, a shaft carried by the stationary portion of the frame, a shaft carried by the movable portion of the frame, a winding-drum carried by one of said shafts, gearing connecting the shaft, and means for adjusting the movable portion of the frame to connect and disconnect said gearing.
- 20 3. An attachment for traction-engines, comprising a supporting-frame having a movable portion, a shaft carried by the stationary portion of the frame, a shaft carried by the movable portion of the frame, a winding-drum carried by one of said shafts, gearing connecting the shafts, means for adjusting the 25 movable portion of the frame to connect and disconnect said gearing, and means for locking said frame in either of its two positions.
- 30 4. An attachment for traction-engines, comprising a supporting-frame, a pair of shafts carried thereby, a winding-drum on one of said shafts, a power-transmitting wheel mounted on the second shaft, gearing connecting the shafts, means for connecting and disconnecting said gearing, a hauling-line 35 connected to the winding-drum, a line-guide, means for supporting the same, an auxiliary shaft, a worm-wheel mounted thereon, a worm carried by the drum-shaft and intermeshing with said worm-wheel, a crank on the auxiliary shaft, and a rod connecting said crank to the line-guide.
- 40 5. An attachment for traction-engines, comprising a supporting-frame, a pair of shafts carried thereby, a winding-drum on one of said shafts, a power-transmitting wheel mounted on the second shaft, gearing connecting the shafts means for connecting and disconnecting said gearing, a hauling-line 45 connected to the winding-drum, a pair of transversely-disposed bars having guiding-slots, a frame guided in said slots, antifriction-rollers journaled in said frame and serving as guides for the hauling-line, a crank-shaft operatively connected to said frame, and worm-gearing connecting the crank-shaft to the drum-shaft.
- 50 6. An attachment for traction-engines, comprising a supporting-frame, a winding-drum mounted thereon, means for revolving said 55 drum, a hauling-line connected to the drum, a pair of vertically-disposed antifriction-roll-

ers mounted in front of and at each end of the drum, and a pair of horizontally-disposed antifriction-rollers arranged on lines parallel with the longitudinal axis of said drum.

7. An attachment for traction-engines, comprising a supporting-frame, a shaft carried thereby, a drum mounted on said shaft, gear-wheels secured to the shaft and drum, a pivoted frame, a shaft carried thereby, pinions mounted on said shaft and adapted to intermesh with the gear-wheels of the drum-shaft, a rock-shaft, notched cams thereon adapted to engage with and move the pivoted frame, and means for locking said frame in elevated or depressed position.

8. An attachment for traction-engines, comprising a supporting-frame, a drum-shaft carried thereby, a winding-drum and gear-wheels carried by said shaft, a pivoted frame, a shaft carried thereby, pinions carried by said shaft and adapted to intermesh with the gear-wheel, a rock-shaft, means for operating the same, notched disks carried by said shafts for actuating the frame, and means for simultaneously locking the frame and disks.

9. An attachment for traction-engines, comprising a stationary and a movable frame, shafts carried by each portion of the frame, a winding-drum carried by one of said shafts, gearing connecting the shaft, a rock-shaft, notched disks for engaging the movable frame and adjusting the position thereof, and spring-pressed locking-rods for locking said frame and disk.

10. An attachment for traction-engines, comprising a stationary frame, a pivoted frame carried thereby, shafts carried by each of said frames, a winding-drum carried by one of said shafts, gearing connecting the shafts, a rock-shaft, notched disks carried by the rock-shaft and adapted to engage with and adjust the position of the pivoted frame, spring-pressed locking-rods for locking the pivoted frame in either depressed or elevated position, the rear ends of said rods having arms for engagement in notches in said disks.

11. An attachment for traction-engines, comprising a stationary frame, a pivoted frame carried thereby, shafts carried by each of said frames, a winding-drum carried by one of said shafts, gearing connecting the shafts, a pair of rock-shafts each having operating-levers, disks carried by one of said rock-shafts, each of said disks having a pair of locking-slots and being provided with a notched portion for engagement with the pivoted frame, a guided locking-rod adapted to engage both the pivoted frame and the slots of the disks, a pair of spring-pressed arms carried by the second rock-shaft, and arms carried by the locking-rods and connected to said spring-pressed arms.

12. An attachment for traction-engines, comprising a main supporting-frame having a pair of shafts, a winding-drum on one of said shafts, a power-transmitting wheel on

the second shaft, a sprocket-wheel mounted on said second shaft and connected to the driving-engine, and an auxiliary frame adapted to be secured to either side of the main frame, said auxiliary frame having bearings for the support of the outer ends of said pair of shafts.

In testimony that I claim the foregoing as my own I have hereto affixed my signature in the presence of two witnesses.

DANIEL W. COMBS.
